UNITED STATES PATENT OFFICE.

HENRY DOBBIN, OF BOUND BROOK, NEW JERSEY, ASSIGNOR TO THE BOUND BROOK WOOLEN MILLS, OF SAME PLACE.

DESIGN FOR CLOTH.

SPECIFICATION forming part of Design No. 12,818, dated March 21, 1882.

Application filed November 25, 1881. Term of patent 7 years.

To all whom it may concern:

Be it known that I, HENRY DOBBIN, a citizen of the Kingdom of Great Britain, residing in the village of Bound Brook, Somerset county, State of New Jersey, have invented and produced a new and original Design for Cloths known as "Fur Beavers," being cloths having a heavy pile or nap, of which the following is a specification, reference being had to the accompanying drawing, forming part thereof.

Heretofore cloths have been ornamented by straight and also diagonal lines, either raised above or depressed below the surface of the cloth, of equal width, and separated by spaces of the cloth of equal width, and all running in the same direction.

My design is different from this, and consists in forming in the length of the cloth, as distinguished from the width thereof, a series of lines which are separated from each other by a space of the surface of the cloth substantially as wide as are the lines themselves. A complete series of these lines is shown at *a a a a a a a*, and I will call them the "equal lines." (Seven are shown in the drawing; but I do not limit myself to that specific number.) Following these equal lines *a a a, &c.*, are three bands, *c c c*, composed of the smooth surface of the cloth. These are of substantially equal width, and the dividing-lines *b b* between them

may be, if desired, somewhat wider or heavier than the lines *a a a, &c.* All these lines *a* and *b* are parallel with each other. This figure then repeats itself, and so continues throughout the entire width of the cloth. The width of the three bands taken, as a whole, relative to the width of the series of lines *a a a, &c.*, is as about two to three. The lines *a a a, &c.*, and the lines *b b* may be elevations above the surface of the cloth instead of depressions below it, if desired, substantially the same optical effect being produced in either case.

I claim—

The design for the surface of cloth herein shown and described, consisting of a series of 45 lines running the length of the cloth, separated from each other by spaces of the surface of the cloth substantially equal in width to the width of the lines themselves, and following this series of lines a space of the smooth surface of the cloth equal to about two-thirds of the width of the lines taken as a whole, which smooth surface is divided by lines into three bands of substantially equal width, which figure then repeats itself.

HENRY DOBBIN.
